JOHN P. FLETCHER, OF THE UNITED STATES ARMY, OF CARLISLE, PENNSYLVANIA,
ASSIGNOR TO COOK LABORATORIES, INC., OF CHICAGO, ILLINOIS, A CORPORATION
OF DELAWARE

HYPODERMIC SYRINGE

Application filed March 11, 1929. Serial No. 345,977.

This invention aims to provide an improved hypodermic syringe of the type having or employing a sealed medicament-container from which the fluid is ejected through 5 the needle.

For illustration, one practicable syringe construction embodying the invention is shown in the appended drawing, in which:

Fig. 1 is a side elevation of the illustrative 10 syringe;

Fig. 2 is a longitudinal section thereof; Fig. 3 is a section on the line 3—3 of Fig. 2, looking in the direction of the arrows and showing the rear parts in end elevation;

Fig. 4 is a cross-section on line 4—4 of Fig. 2, looking in the direction of the arrows and showing fore parts in end elevation;

Fig. 5 is a sectional elevation, the section being taken on the line 5—5 of Fig. 2 and 20 looking in the direction of the arrows.

The illustrative syringe contains, as a removable operative component, a sealed medicament container with needle-holding and ensheathing means, constructed as a unit. 25 The medicament container is represented by a glass tube 1 having rubber sealing plugs or stoppers 1^a and 1^b between which is confined the anesthetic solution or other medicament fluid to be dispensed. Said container has a 30 needle-holder 2 carrying an injecting needle 3 in operative position for injection into the patient's tissue. The needle is sealed by a glass sheath 4 extending from the container and adapted to be removed to expose the injecting needle.

The combined sealed medicament-containing and needle-carrying and ensheathing unit is mounted in an instrument body 5 constructed to receive and hold the unit and to permit forward protrusion of the needle-carrying and ensheathing extension of the unit. As shown more clearly in Fig. 1, said instrument body 5 of the particular instrument shown is constructed as a skeletonized tubular-like holder for the medicament-container, said holder being of larger internal diameter than the external diameter of the medicament-container, and, by virtue of its 45 skeletonized construction, providing a lateral

longitudinal opening wide enough to permit lateral or sidewise insertion of the medicament-container into the instrument body.

At its fore end, the instrument body is constructed with a fixed head 6 having a radial slot 7 to receive the needle sheath 4 when the unit is inserted in the instrument body. Swiveled or rotatably mounted on said fixed head 6 is a head 8 having a similar slot 9. To permit insertion of the unit, the head 8 55 may be turned or adjusted to align the slots 7 and 9, so as to accommodate the needle-enclosing sheath 4. After inserting the unit and positioning it as shown in the drawing, the head 8 may be turned or adjusted, for instance to the position shown in Figs. 2 and 5, so as to move the slot 9 out of alignment with the slot 7. Thus the heads 6 and 8 provide in effect a composite head having a central opening through which the needle sheath 60 protrudes and into which central opening the said sheath may be admitted through the slots 7 and 9 when aligned; the outer member of said composite head adapted to be turned or adjusted to close the entrance to 65 the central opening, thus serving as a locking device to prevent any accidental displacement of the needle-ensheathing end of the unit after it is inserted.

The instrument body has a rear head 10 70 shown integral with and extending as a flange from the rear of the instrument body. This head is constructed to provide a sufficient bearing 11 for the plunger rod 12. Said 75 plunger rod is adapted to enter the glass tube 1 and drive in the rear plug 1^a thereof to eject the fluid contents of the medicament-container through the needle, after communication with the needle is established as hereinafter explained. An enlarged head 13 on the inner end of the plunger rod prevents retraction of the plunger rod from the instrument. A handle or thumb knob 14 is provided on the rear end of the plunger rod. 80 This thumb piece 14 may be screwed on a reduced threaded terminal of the plunger rod as indicated in dotted lines in Fig. 2.

The head 10 has attached thereto at 15 a resilient plate or spring finger 16 which ex- 100

tends transversely through the instrument body as shown in Figs. 2 and 3. This plate has a central opening to permit the plunger rod and its head 13 to pass therethrough into the glass tube. The roughened upper free end 17 of the spring plate may be pressed back by the thumb to retract the spring plate when inserting or removing the unit. Normally the spring plate presses forward against the butt end of the medicament-container and thus presses the container forward so that its fore end, or the shoulder between the container and its needle-ensheathing extension, bears against the head 6. When inserting the medicament-containing and needle-ensheathing unit, the spring plate 16 will be pressed back by the butt end of the unit until the unit is positioned in proper alignment with the instrument, whereupon the spring will press the unit forward to bear against the abutment provided by the head 6.

The instrument body or holder for the medicament-container has near its rear end a pair of spring clasps 18, shown more clearly in Fig. 4. These clasps are positioned to receive and embrace the glass tube 1. Thus when the medicament-containing and needle-ensheathing unit is inserted in the instrument, with the needle-ensheathing extension thereof seated in the center of the fore end of the instrument, and with the rear portion of the tube 1 seated in the clasps 18, the unit is properly aligned with the instrument and in position, as shown in Fig. 2, to admit the plunger 13 into the glass tube.

After inserting the unit, the glass sheath 4 should be removed to expose the injecting needle, and communication between the needle and the fluid chamber of the sealed medicament-container should be established. With the particular unit selected for illustration, the needle-holding extension 2 of the medicament-container is provided by an extension of the sealing plug 1^b, and the glass needle sheath 4, which in this instance is separate from the glass medicament-containing tube 1, is fitted on and sealed by said extension. Thus the sheath may be removed by withdrawing it from said extension; although the sheath, being of glass, would of course be susceptible of removal by nicking or filing and then breaking it off around the needle-holding extension. The needle is shown embedded in the plug 1^b with the inner pointed end of the needle closely adjacent to but not axially piercing the inner wall of said plug, leaving a sufficient thickness of material between the liquid and the inner end of the needle for effective sealing of the liquid during transportation and handling of the unit, yet which may be readily pierced by a slight relative movement between the plug and needle. This piercing may be accomplished by a slight inward thrust of the needle, the

inward movement thereof being limited by the intermediate needle enlargement 3^a. An inward thrust of the needle to cause the piercing may be aseptically accomplished by utilizing the removed needle sheath as a convenient pusher and pushing with the end of said sheath against the needle enlargement 3^a. Communication having been established, the inward forcing or continued inward forcing of the piston plug 1^a by the plunger rod 75 will eject the fluid contents of the medicament-container through the needle. With said specific unit, the plug 1^b preferably has a flange interposed between the end of the glass tube and the head 6, serving as a gasket 80 or to cushion the end of the glass tube 1 against end thrust during the fluid-ejecting operation, and said plug 1^b also preferably has an inwardly-opening axial recess providing an annular wall on which the hydrostatic 85 pressure acts during the fluid-ejecting operation, tending to press said wall more tightly against the interior of the tube and thus promoting the maintenance of a good seal.

The construction described is characterized by simplicity and convenience, permits a quick assemblage of the syringe or injection-administering organization for operative use, and the holding and operating instrument in which the unit is contained is adapted to be made as a comparatively inexpensive article. The sealed medicament-containing and needle-ensheathing unit may be easily inserted laterally as already explained, the spring plate 16 pressing the unit forward 100 to abut the fore end of the medicament-container against the head 6, whereupon the head 8 may be turned sufficiently to hold the needle-ensheathing extension and prevent accidental displacement. The sheath 4 may 105 then be removed, and the instrument body may conveniently be held between the first and second fingers while the thumb presses on the thumb piece 14 to force in the plunger rod so as to drive in the plug 1^a and eject the 110 contained fluid through the needle.

The construction described exemplifies a hypodermic syringe comprising an instrument having therein, as a removable operative component, a sealed medicament-containing unit with an injecting needle and sheath therefor carried by and extending from the fore end of the container, the instrument having its fore end constructed to abut the fore end of the container and accommodate protrusion of the ensheathed needle and to permit removal of the sheath, and being constructed to permit insertion and removal of the unit and having suitable ejector means for operating the unit. The specific instrument shown is one suitable instrument for use in conjunction with such unit for the purposes of the type of organization referred to, and in itself embodies inventive features of distinctive advantage as hereinbefore in- 130

dicated. The unit exemplifies a medicament-container and needle-carrying and ensheathing syringe unit embodying a sealed medicament tube with a sealing plug and operatively held needle to pierce said plug by relative movement of the plug and needle under force applied on one of them, and the unit in itself embodies features of the invention.

It will be understood that the invention is not limited to the particular embodiment herein illustrated and described; also that features of the invention may be advantageously used in various different combinations and sub-combinations.

15 What I claim as my invention is:

1. A hypodermic syringe comprising, in combination, a sealed medicament container comprising a tube having a fore closure to be pierced by a needle and having a displaceable rear plug; a holder in which said container is removably mounted said holder having an abutment for the fore end of the container and a spring plate to press against the butt end of the container and hold it in engagement with said abutment; means to hold a needle in position for piercing the fore closure of the container; and a plunger arranged to enter said tube and drive in the piston plug; the said spring plate embodying an annular portion to permit entry of the plunger into the tube.

2. A syringe instrument for holding and operating a medicament-containing unit having a needle-ensheathing extension, said instrument constructed to admit the unit sidewise and having a radially slotted fore part to admit the needle-ensheathing extension of the unit, said fore part embodying an adjustable member which can be adjusted to close the slotted fore part around the needle-ensheathing extension and thereby lock the unit in place, and said instrument having a rearwardly mounted plunger and resilient means to bear on the butt end of the unit to press it forward against an abutment provided by the fore part of the instrument.

3. A syringe instrument for holding and operating a medicament-containing unit having a needle-ensheathing extension, said instrument constructed to admit the unit sidewise and having a radially slotted fore part to admit the needle-ensheathing extension of the unit, said fore part embodying an adjustable member which can be adjusted to lock the unit in place, and said instrument having a rearwardly mounted plunger.

4. In a cartridge syringe, a cartridge-holder having a lateral opening to permit insertion of the cartridge, said holder constructed to provide an abutment for the fore end of the cartridge and having a fixed rear head with a cartridge-operating plunger therein and a spring plate arranged to bear on the butt end of the cartridge so as to press the cartridge forward against said abutment,

said spring plate having a free end projecting through said opening and bent rearwardly and adapted to be engaged by the thumb for drawing back the spring plate to release the cartridge while also facilitating the camming of the butt end of the cartridge against the spring plate as the cartridge is inserted.

5. A syringe instrument for use with a cartridge having a needle-ensheathing extension, said instrument comprising a holder having a lateral opening for insertion of the cartridge and having at its fore end a fixed radially slotted head and a rotatable radially slotted head, the slots of which heads may be registered to permit side wise insertion of the said needle-ensheathing extension, said slots when out of registry cooperating to provide a central circular opening through which said extension can protrude.

In testimony whereof, I have signed my name to this specification.

JOHN P. FLETCHER.
